Attorney

UNITED STATES PATENT OFFICE.

LLOYD G. COPEMAN, OF FLINT, MICHIGAN.

REFRIGERATOR-DOOR CONSTRUCTION.

Application filed June 25, 1923. Serial No. 647,598.

To all whom it may concern:

Be it known that I, LLOYD G. COPEMAN, a citizen of the United States, residing at Flint, in the county of Genesee and State of Michigan, have invented certain new and useful Improvements in Refrigerator-Door Construction, of which the following is a specification.

This invention relates to refrigerator doors and has for its object a refrigerator lining construction of cast tile and provided with means for preventing the moisture condensed on the door from draining out the side of the refrigerator so as to get into the joints of the door frame or leave a wet spot on the floor outside the door.

In the drawings:

Fig. 1 is a fragmentary inside elevation of the tile.

Fig. 2 is a vertical section on the line 2—2 of Fig. 1.

Refrigerator doors are ordinarily built up of a wooden block construction forming a thick stepped door which is ordinarily lined with zinc, galvanized iron, or some form of enamelled metal. It is the object of the present invention to completely do away with this built up construction which is open to difficulty if moisture gets into the joints that swell with the moisture and shrink when they become dry, finally pulling to pieces and also making an unsightly and unsanitary perishable structure.

In place of this construction I cast a hollow tile structure which is formed of a concrete, porcelain, or stone material which is originally semi-fluid but which after the casting operation becomes a solid stone. This construction may be made of various concrete composition materials; I prefer to use an oxide-chloride cement composition. This is preferably composed of magnesium oxide,

sand (crystal flake) soft silex (ground flint), ground asbestos, lithopone and magnesium chloride, 30 Baumé. This makes a strong 45 hard stone when it sets. This I preferably cover on the inside with some suitable filler material which will fill up any pores or depressions and then coat the same with enamel, preferably air drying enamel of the 50 pyroxylin group, such as the well known "Pyrolin" put out by the E. I. Dupont de Nemours Co. of Wilmington, Delaware.

One of the special features of this tile is that there is cast integral therewith, a drip 55 flange *a* which protrudes down below the bottom of the pyramidal inside portion of the tile. In order to accomplish this I use any suitable die or mold.

What I claim is:

1. In a refrigerator construction, a door lining in the form of a hollow tile block provided with a drip flange.

2. In a refrigerator construction, a door lining in the form of a hollow tile open on 65 one side and having on the inside face an integral extension forming a drip flange.

3. In a refrigerator construction, a door lining in the form of a molded hollow tile having one side open and the other side 70 pyramidal with the inside facing of such pyramidal portion extending down at the bottom to form a drip flange.

4. In a refrigerator construction, a door lining in the form of a molded hollow 75 stepped tile provided on the inside face with an integral depending drip flange portion.

5. In a refrigerator construction, a door lining in the form of a molded stone-like tile in the form of a hollow stepped block 80 provided on its inside face with an integral depending drip flange.

In testimony whereof, I affix my signature.
LLOYD G. COPEMAN.
